UNITED STATES PATENT OFFICE

145,357

DESIGN FOR A WATCH BRACELET

Robert Lambert, Fullerton, Nebr.

Application January 11, 1946, Serial No. 125,450

Term of patent 7 years

(Cl. D45—4)

To all whom it may concern:

Be it known that I, Robert Lambert, a citizen of the United States, residing at Fullerton, in the county of Nance and State of Nebraska, have invented a new, original, and ornamental Design for a Watch Bracelet, of which the following is a specification, reference being had to the accompanying drawing, forming part thereof.

In the drawing:

I claim:

The ornamental design for a watch bracelet, as shown.

ROBERT LAMBERT.
